CLAIM

The ornamental design for “lattice panel with octagonal pattern modules”, as shown as claimed and described.

DESCRIPTION

FIG. 1 is a front elevation view of a lattice panel showing my new design for a lattice panel with octagonal pattern modules; and

FIG. 2 is a bottom view, which is the same as the top view, of the lattice panel with octagonal pattern modules;
FIG. 3 is a right side view, which is the same as the left side view, of the lattice panel with octagonal pattern modules; and,

FIG. 4 is a rear elevation view of the lattice panel with octagonal pattern modules.
